UNITED STATES PATENT OFFICE.

ANDREW ROBERT SHANNON, OF WATERTOWN, NEW YORK.

FIRE-ESCAPE.

SPECIFICATION forming part of Letters Patent No. 509,106, dated November 21, 1893.

Application filed September 30, 1892. Serial No. 447,379. (No model.)

To all whom it may concern:

Be it known that I, ANDREW ROBERT SHANNON, of Watertown, in the county of Jefferson, in the State of New York, have invented new 5 and useful Improvements in Fire-Escapes, of which the following, taken in connection with the accompanying drawings, is a full, clear, and exact description.

My invention relates to improvements in 10 fire escapes of the class described and claimed in my previous patent, No. 463,670, dated November 24, 1891, and has for its object the production of a device of great practicability, simplicity, and efficiency.

15 To this end it consists, essentially, in a lengthwise guide on the outside of a building wall, a carriage movable up and down the guide, a revolute shaft having one end connected to the carriage for raising and lowering the same as the shaft is revolved, a counter-balance for the carriage connected to the shaft, a liquid containing shell preferably mounted on the inner side of the building wall and formed with a pair of connected 25 chambers, a pair of drums at the opposite extremities of the liquid containing shell, one of which is revolved by the inner end of said shaft, a plunger movable in one chamber of said shell and provided with a liquid passage, 30 a movable valve for opening and closing said passage, a partition in the other chamber of the shell, and a flexible connection movable through said partition and having its opposite extremities passed over said drums and connected to said plunger.

The invention furthermore consists in the detail construction and arrangement of the parts, all as hereinafter more particularly described and pointed out in the claims.

40 In describing this invention, reference is had to the accompanying drawings, forming a part of this specification, in which, like letters indicate corresponding parts in all the views.

45 Figure 1 is a top plan view of my improved fire escape, a portion of its supporting building wall being shown in section and its upper protecting case or cover being removed. Fig. 2 is an elevation of the parts as shown at Fig. 1, 50 the upper case or cover being here illustrated in section. Fig. 3 is vertical sectional view, taken on line —3—3—, Fig. 1, the carriage

being omitted, the lower end of the counterbalance chamber broken away, and the drum on the revolute shaft illustrated as in the 55 same vertical plane as the counterbalance for the carriage for the purpose of more clearly illustrating the construction and operation of said parts and the flexible connection between the two. Fig. 4 is a vertical sectional view, 60 taken on line —4—4—, Fig. 1, representing particularly the carriage, the central portion of which is broken away, the drum for raising and lowering the carriage, and the flexible connection between these parts. Figs. 5 and 6 are 65 vertical sectional views, taken respectively on lines —5—5— of Fig. 2 and —6—6—, Fig. 5, illustrating the general construction and arrangement of the liquid containing shell on the inner side of the supporting building 70 wall, the plunger and drums within said shell and the flexible connection passed over said drums and connected to the plunger. Fig. 7 is a top plan view, partly in section, of the 75 detached carriage and its guide, a dotted line illustrating the plane of the building wall. Fig. 8 is an enlarged transverse sectional view, taken on line —8—8—, Fig. 5. Fig. 9 is a vertical sectional view, taken on line —9—9—, Fig. 8. Fig. 10 is an enlarged transverse sectional view, taken on line —10—10—, Fig. 5. Fig. 11 is a vertical sectional view, taken on line —11—11—, Fig. 10, and Fig. 12 is an enlarged transverse sectional view, taken on line —12—12—, Fig. 2. 85

My improved fire escape is of such construction that its carriage is automatically supported in its elevated position, is free to descend as soon as occupied, and is prevented from rapid descent, even when heavily laden. 90 It is also of such construction that the carriage may be stopped or held at any desired height to remove persons from a floor beneath the top floor of the building.

—A—represents an outer supporting building wall, and —a—*a'*— the floors of any suitable construction of building to which it may be desired to attach my improved fire escape.

—B— is a suitable carriage supported at the outside of the building wall —A—, and —C— a revolute shaft passed horizontally through said wall and arranged with its outer end suitably connected to the carriage —B— for raising and lowering the same as the shaft

is revolved. As best seen at Figs. 1, 2, 4, and 7, the carriage —B— is here illustrated as circular in cross section, and as provided with an opening —B'— in the portion of its upright 5 wall directly opposite to the window —A'— in the wall —A—.

—B²— is a suitable door for closing the opening —B'— having its upper and lower edges movable in curved grooves —b— in the 10 wall of the carriage —B— and its outer or front side provided with a hand engaging projection —b'—. A suitable counterweight —B³—, Fig. 4, is connected to the inner face of said side of the door —B²— by a cord 15 —B⁴— passing over a suitable pulley —B⁵— and serves to normally close said door.

In entering the carriage —B— the door is pulled backwardly against the force of the counterweight —B³—, and, when the person 20 desiring to use the carriage, is safely within the same, the door is released and is immediately closed automatically, thus protecting the occupant should flames dart or project from the portion of the building, along which 25 the carriage moves in its descent.

—B⁶— represents a support or bar above the carriage —B—, and —B⁷— links having their inner or upper ends connected to said support or bar, and their outer or lower ends 30 to lugs —B⁸— on the top of the carriage.

—C'— is a drum upon the outer end of the shaft —C—, and —c—c—c—c— peripheral flanges on said drum between which are wound the upper ends of flexible connections 35 or straps —D—D—D—. These upper ends of the straps —D—D—D—D— are firmly secured to the drum —C'— by a wedge shaped cross bar —c'— movable in the peripheral face of the drum —C'—, and their lower ends 40 are extended downwardly at one side of the shaft —C—, and are secured by a similar cross bar —c²— movable in the upper face of the support —B⁶—, which forms virtually the top of the carriage —B—.

45 Upon the shaft —C— is a second drum —C²— interposed between the former drum —C'— and the building wall —A—.

—E— is a flexible connection or strap having one end secured to the drum —C²— by 50 suitable fastening means —e—, and the other end passed downwardly at the side of the shaft —C— opposite to that adjacent to the lower end of the connections —D—D—D—, and extended within a chamber —F— at one 55 side of the carriage —B—, and connected at —f— to a movable counterweight —F'— for the carriage —B—. The chamber —F— extends vertically along the outer side of the building wall —A—, and is supported in position by brackets —A²—A²— projecting therefrom, as shown at Figs. 1 and 2, and, as 60 presently described, this chamber is of such construction as to form a guide for the carriage —B— in its movement.

65 At the upper end of the chamber —F— are anti-friction rollers —f'—f'— between which the end of the connection or strap —E— is

passed for guiding the same in its movement and straightening any kinks therein.

—F²— is a spring having its upper end 70 suitably secured to a plate —f²— on the underside of the top wall of the chamber —F—, and its lower end adapted to encounter the top face of the counterbalance, as the same assumes its elevated position, thus causing 75 the carriage —B— to end its downward movement gradually and preventing injury or battering of the top wall of the chamber —F—.

The counterweight —F'— slightly overbalances the weight of the carriage, and, when 80 the carriage is empty, gravity draws the counterweight down to the base of the chamber —F—, thus revolving the shaft —C— in the direction shown by arrow —1— at Figs. 3 and 4, and elevating the carriage to its position 85 shown at Figs. 1, 2, and 4. When the carriage is occupied the additional weight depresses the same, and raises the counterbalance to its position shown at Fig. 3, and, after the occupant emerges, both the carriage 90 and the counterbalance assume their normal positions.

The drum —C²— is merely a simple means of connecting the counterweight —F'— to the carriage —B— in order that, as the counterweight descends, the carriage may be raised and vice versa, but it will be understood that other connecting mechanism may be used for effecting this result and that the drum —C²— may be dispensed with entirely and the connection between the car and the counterbalance may be continuous and be passed over a single drum.

—G— represents arms extending laterally from the upper and lower edges of a portion 105 of the carriage —B—, and —d— upper and lower spindles journaled in said arms.

Journalized upon the extremities of the arms —G— are anti-friction rollers —g— engaging the outer edges of flanges —F³—F³— extending from the opposite sides of the upright wall —F⁴— of the chamber —F—. —g'— represents similar rollers mounted upon the spindles —d— with their peripheral faces bearing against the outer face —f³— of the 115 wall —F—. This peculiar construction of the bearing faces upon the counterbalance chamber and the anti-friction rollers on the carriage serves to reduce to a minimum the amount of friction incidental to the movement 120 of the carriage, and adds greatly to the efficiency of my invention.

At the base of the carriage —B— I provide a false bottom or contact plate —B⁹— secured to the lower end of springs —B¹⁰— having 125 their upper ends attached to the base of the carriage —B—. This spring actuated false bottom also aids in preventing a sudden stoppage of the carriage, and obviating the jar, which would otherwise be felt.

The carriage —B—, the counterbalance chamber —F—, the outer end of the shaft —C—, and the drums —C'—C²— thereon are 130 protected from the elements by a hood —B'—

secured to and projecting from the building wall —A—, and, as is evident, this hood may be of any desirable form or construction.

In order to regulate the downward movement of the carriage —B— and prevent its sudden descent when heavily laden, I provide an upright liquid containing shell —H—, Figs. 1, 2, 5, 6, 7, and 8, which is supported on the inner side of the building wall —A— by suitable brackets —h—h—. This shell —H— is provided with two chambers —H'—H²— arranged side by side with their upper and lower ends connected together. The inner end of the shaft —C— projects within the upper end of the shell —H—, and provided thereon is a sprocket wheel —I—. Within the lower end of the shell I journal an idler —I²—, and passing around said sprocket and idler is a flexible connection —J—, a portion of which is formed of links —j—j— for engaging the teeth of the sprocket wheel.

—K— is a plunger movable in the left-hand chamber —H'— of the shell —H—, and provided with lengthwise liquid passages —k—k—, best seen at Figs. 6 and 9. At the opposite extremities of the plunger —K— are flexible annular shoulders —K'—K'— closely fitting the chamber —H'—, and, upon the top of the plunger, are movable valves —K²—K²— of any suitable construction for normally closing the upper ends of the liquid passages —k—k— and opening said ends of the passages —k—k— for facilitating the downward movement of the plunger and permitting an equilibrium of the pressure in both chambers.

—L— is a partition at the base of the chamber —H²— formed with a lengthwise perforation —l— for permitting the passage of the flexible connection —J—. The passage —l— is sufficiently small to limit the rate of flow of the liquid from the lower end of the chamber —H²— into the corresponding end of the chamber —H'—. As the carriage —B— descends, as described, the shaft —C— is revolved in the direction shown by arrow —2— at Fig. 5, and the plunger —K— is drawn upwardly, thus firmly forcing the valves —K²—K²— downwardly and closing the liquid passages —k—k— and compressing the liquid within the upper portions of the chambers —H'—H²—. It will readily be apparent that this construction of liquid containing shell and plunger permits the carriage to descend only at a definite and comparatively slow rate of speed, as the liquid can only flow at a comparatively slow rate of speed through the passage —l— from the base of the chamber —H²— to the lower end of the chamber —H'—, and the force tending to elevate the plunger —K— at a greater speed than that permitted by the escape of the liquid through the passage —l—, serves only to create a back pressure of the liquid, which regulates effectually the upward movement of the plunger —K—.

To facilitate the manufacture of the shell —H— it is composed of the central section —h'—, which is provided with the chambers

—H'—H²— and the lower and upper head —h²—h³—. It is extremely essential that the chambers —H'—H²— remain constantly filled with liquid, and accordingly I provide at the upper end of the head —h³— a feeding chamber —h⁴—, the lower wall —h⁵— of which forms a portion of the top wall of the head —h³—, and is provided with an outlet opening —h⁶—, Figs. 5 and 11, discharging into said head. A suitable float valve —h⁷— having its stem movable in the opening —h⁶—, is normally elevated by the liquid to close said opening, and quickly drops upon the presence of air, or a slight vacuum within either of the chambers —H'—H²— to permit the liquid to feed into said chambers from the chamber —h⁴—. This valve is restrained in its downward movement by stop shoulders —h⁸— adapted to bear against the top face of the bottom wall —h⁵— of said feeding chamber —h⁴—, and, as soon as the chambers become entirely filled, it is again elevated to its normal position. To further insure the maintenance of a full supply of liquid within the chambers —H'—H²— I provide within the feed chamber —h⁴— an inner upright chamber —h⁹— of less height than the chamber —h⁴— having its upper end closed and its lower end opening through the wall —h⁵— into the head —h³—. The chamber —h⁹— is formed with a removable cap —h¹⁰—, and, as the liquid, which is preferably oil, is filled within the shell —H—, the air at the extreme upper end of the chambers —H'—H²—, is free to escape into the chamber —h⁹—, and is compressed as the level of the liquid in the feed chamber —h⁴— rises above that of the liquid in the chamber —h⁹—, as illustrated at Fig. 5. Consequently the presence of air in the chambers —H'—H²— is entirely prevented, and said chambers are constantly filled with liquid. It will thus be readily understood from the foregoing that the downward movement of the carriage is practically and effectively regulated by the liquid containing shell —H—, and that the carriage always descends at substantially the same rate of speed.

As thus far described the carriage of my invention, when unoccupied, normally ascends to the top of the building, and, in order to enable me to stop the carriage at any desired elevation should it be required to receive the occupants of a building stationed beneath the top floor, I provide suitable actuating mechanism —M—, which is under the control of an operator on the ground at the side of the building. As preferably constructed this actuating mechanism consists of a sprocket chain —m— having one end passed around a wheel —m'— mounted on a spindle —m²— passed through the base of the building wall —A— and the other passed over a sprocket —m³— on the shaft —C—. A crank or other hand engaging piece —m⁴— is secured to the outer end of the spindle —m²—, and, as the spindle is revolved, the shaft is rotated and the carriage positively elevated irrespective

of its counterbalance. The carriage may then be held at any desired elevation by applying sufficient force to the handle to prevent the downward movement of the counterbalance

5 —F'—.

The operation of my invention will be readily perceived from the foregoing description and upon reference to the drawings, and it will be particularly noted that the same is 10 simple and practical in operation, and is durable and effective in use. It will be readily understood, however, that the detail construction and arrangement of the parts of my improved fire escape may be considerably 15 changed without departing from the spirit of my invention.

Having thus fully described my invention, what I claim as new, and desire to secure by Letters Patent, is—

20 1. In a fire escape, the combination of an upright guide having a lengthwise bearing face, and a pair of lengthwise bearing faces extending at an angle with the former face and arranged on opposite sides thereof, a carriage movable along said guide, arms projecting from the carriage, a spindle having its opposite ends adjustably mounted in said arms, an anti friction wheel on the spindle bearing against the former face, and anti 25 friction wheels journaled in said arms and bearing against the latter faces, substantially as and for the purpose set forth.

2. In a fire escape, the combination of an upright guide having upright front and side 30 bearing faces, a carriage movable along the guide, a pair of split bands encircling the upper and lower ends of the carriage and having their ends separated and provided with arms extending laterally toward said guide 35 and formed with slots, rollers journaled on said arms and movable on the side bearing faces of said guide, a spindle having its opposite ends adjustably mounted in said slots, a roller mounted on said spindle and bearing 40 against the front bearing face of the guide 45 and means for raising and lowering said carriage, substantially as and for the purpose specified.

3. In a fire escape, the combination of a 50 movable carriage, a revolving shaft for raising and lowering said carriage, a liquid containing shell, formed with a pair of connected chambers a pair of drums at the opposite ends of said shell, one of which is revolved by 55 said shaft, a plunger movable lengthwise in one of said chambers, and a connection passed over the drums with its opposite extremities secured to the plunger, substantially as and for the purpose specified.

60 4. In a fire escape, the combination of a movable carriage, a revolving shaft for raising and lowering said carriage, a liquid containing shell, formed with a pair of connected chambers a pair of drums at the opposite 65 ends of said shell, one of which is revolved by said shaft, a plunger movable lengthwise in one of said chambers and formed with a lon-

itudinal liquid passage, a connection passed over the drums with its opposite extremities secured to the plunger, and a movable valve 70 at one extremity of the liquid passage in said plunger, substantially as described.

5. In a fire escape, the combination of a 75 movable carriage, a revolving shaft for raising and lowering said carriage, a liquid containing shell formed with a pair of connected chambers, a pair of drums at the opposite ends of said shell, one of which is revolved by said shaft, a plunger movable lengthwise in one chamber of the shell, a partition in the 80 other chamber of the shell, and a flexible connection movable in said other chamber of the shell through said partition and arranged with its opposite extremities extended into the former chamber and connected to the 85 plunger, substantially as specified.

6. In a fire escape, the combination of a 90 movable carriage, a revolving shaft for raising and lowering said carriage, a liquid containing shell, formed with a pair of connected 95 chambers a pair of drums at the opposite ends of said shell, one of which is revolved by said shaft, a plunger movable lengthwise in one of said chambers, a connection passed over the drums with its opposite extremities secured 100 to the plunger, a liquid feeding chamber, and a valve between said shell and chamber for automatically feeding liquid into the shell, substantially as set forth.

7. In a fire escape, the combination of a 105 movable carriage, a revolving shaft for raising and lowering said carriage, a liquid containing shell, formed with a pair of connected 110 chambers a pair of drums at the opposite ends of said shell, one of which is revolved by said shaft, a plunger movable lengthwise in one of said chambers, a connection passed over the drums with its opposite extremities secured 115 to the plunger, a liquid feeding chamber, a valve between said shell and chamber for automatically feeding liquid into the shell, and a chamber within the feeding chamber having one extremity opening into the shell and having the other extremity closed, substantially as set forth.

8. In a fire escape, the combination of a 120 movable carriage, a revolving shaft for raising and lowering said carriage, a liquid containing shell, formed with a pair of connected 125 chambers a pair of drums at the opposite ends of said shell, one of which is revolved by said shaft, a plunger movable lengthwise in one of said chambers, a connection passed over the drums with its opposite extremities secured 130 to the plunger, a spindle beneath said shaft, and connections, substantially as described, between said shaft and spindle, whereby the shaft is rotated as the spindle is revolved, substantially as described.

9. In a fire escape, the combination with 135 the wall of a building; of a movable carriage on the outside of the wall, a revolving shaft passed through said wall and having one extremity connected to the carriage for raising

and lowering the same, a liquid containing shell formed with a pair of connected chambers on the inside of the wall of the building, a pair of drums at the opposite ends of said shell, one of which is revolved by the inner end of said shaft, a plunger movable lengthwise in one of said chambers, a connection passed over the drums with its opposite extremities secured to the plunger, a spindle 5 beneath the shaft, and power transmitting mechanism, substantially as described, arranged on the inside of the building between said shaft and spindle for revolving the shaft as the spindle is rotated, substantially as described.

10. In a fire escape, the combination of a movable carriage, a revolving shaft for raising and lowering said carriage, a liquid containing shell, formed with a pair of chambers 20 a pair of drums at the opposite ends of said shell, one of which is revolved by said shaft, a plunger movable lengthwise in one of said chambers, a connection passed over the drums with its opposite extremities secured to the 25 plunger, a counterbalance for the carriage, a drum on said shaft, and a connection between said counterbalance and drum, substantially as specified.

11. In a fire escape, the combination of a 30 longitudinal guide, a carriage movable on said guide, a shaft having one end connected, substantially as described, to said carriage, for raising and lowering the same as the shaft is revolved, a liquid containing shell formed 35 with a pair of connected chambers, a pair of drums at the opposite ends of said shell, one of which is revolved by said shaft, a plunger movable lengthwise in one chamber of the shell, a partition in the other chamber of the 40 shell, and a flexible connection movable through said partition in the other chamber of the shell and arranged with its opposite

extremities extended into the former chamber and connected to the plunger, substantially as described.

12. In a fire escape, the combination of a movable carriage, a revolving shaft for raising and lowering said carriage, a liquid containing shell formed with a pair of connected chambers, a pair of drums at the opposite 50 ends of said shell, one of which is revolved by said shaft, a plunger movable lengthwise in one chamber of the shell and provided with a pair of openings therethrough, valves at the upper ends of said openings, a partition in 55 the other chamber of the shell, and a flexible connection movable in said other chamber of the shell through said partition and arranged with its opposite extremities extended into the former chamber and connected to the 60 plunger, substantially as and for the purpose described.

13. In a fire escape, the combination of a movable carriage, a revolving shaft for raising and lowering said carriage, a liquid containing shell formed with a pair of connected 65 chambers and provided at its upper end with a removable cap, a pair of drums at the opposite ends of said shell one of which is revolved by said shaft, a plunger movable 70 lengthwise in one of said chambers, and a connection passed over the drums with its opposite extremities secured to the plunger, substantially as and for the purpose specified.

In testimony whereof I have hereunto 75 signed my name, in the presence of two attesting witnesses, at the town of Cobourg, in the county of Northumberland, in the Province of Ontario, Canada, this 20th day of September, 1892.

ANDREW ROBERT SHANNON.
